UNITED STATES PATENT OFFICE.

MARK YOUNG, OF KALAMAZOO, MICHIGAN.

CUTTING AND RAVELING MACHINE FOR RUG MATERIALS.

SPECIFICATION forming part of Letters Patent No. 663,210, dated December 4, 1900.

Application filed September 16, 1897. Serial No. 651,846. (No model.)

To all whom it may concern:

Be it known that I, MARK YOUNG, a citizen of the United States, residing at Kalamazoo, in the county of Kalamazoo, State of Michigan, have invented a new and useful Cutting and Raveling Machine for Rug Materials, of which the following is a specification.

This invention relates to machines for raveling out the two opposite edges of a strip of carpet or other rug material by means of a roller-feed and revoluble knives.

One object of my invention is to effect a cutting of the material into strips by the same machine and during the same operation which does the raveling.

A further object is to provide adjustable means for operatively connecting the parts of the machine together; and a further object is to provide saws and improved guide, all as more particularly set forth in detail below.

In the accompanying drawings, forming a part of this specification, Figure 1 is a plan of the machine; Fig. 2, an elevation of Fig. 1 looking from a point above Fig. 1, showing the adjustable gears connecting the working parts of the machine; Fig. 3, a broken elevation of some of the parts shown in Fig. 1 looking from a point at the right and showing a portion of the guide in section and other parts broken away; Fig. 4, a sectional elevation on line *c c* in Fig. 1 and looking from a point at the left and on line *e e* in Fig. 2 looking from a point at the right and showing the operation of both saws on the edges of the rug material; Fig. 5, an enlarged detail of one of the gear-adjusting arms, shown dotted in Fig. 2; and Fig. 6 is a section on line *v* in Fig. 5 looking from a point above.

Referring to the parts of the drawings pointed out by numerals, 7 and 8 are portions of the machine-frame in which the two cutter-shafts 10 and 11 and the two roller-feed shafts 27 and 28 have bearings, Figs. 1, 4, and 6. The cutters or revolving knives 13 and 14 are one above the other and act on the material 15 like a shear, as shown in Figs. 1 and 3. The feed-rollers 16 and 17 are also one above the other a little in advance of the knives, Figs. 1, 3, and 4. By each side of the feed-rolls 13 and 14 are the saws 18 and 19, one on each side, as in Fig. 4, in position to act on the material and ravel it at each edge, as shown in

said figure. These saws are mounted on shafts 20 and 21, which are at right angles to the feed-roller shafts and have bearings in a branch 55 portion 22 of the frame. The bearings of the saw-shafts may be like those in Fig. 4 at 23 and 24, so as to adjust the saws nearer together or farther apart by turning the screws 25, or the bearings may be plain, as at 26 in Fig. 1, 60 and have no provision for adjustment.

One of the purposes of adjusting the shafts which carry the raveling-saws is to control the depth of raveling desired to be performed.

On the outside of portion 8 of the main 65 frame and attached to the ends of the roller-feed shafts are gears 29 and 30. The gear 29 is attached to the shaft 27, and the gear 30 is attached to the shaft 28. To the same ends of the cutter-shafts 10 and 11 are attached 70 like gears 31 and 32, as in Fig. 2. The gears 31 and 32 are connected by intermeshing gears 33 and 34. The lower feed-roller gear 30 is connected with the lower cutter-shaft gear 32 by a gear 35, and the upper feed-roller gear 75 29 is connected with the upper feed-roller gear 31 by a gear 36. These gears 33, 34, 35, and 36 are idlers and have bearings in adjustable arms hereinafter described. All these gears are indicated in Fig. 2 in an unfinished 80 manner merely to show their relation and position in the machine. Some of them are also shown in Figs. 1 and 4. The adjustable arms are shown dotted in Fig. 2 at 38, there being four of them; but for a definite showing of their construction reference should be had to Figs. 5 and 6, where they are shown enlarged—that is, one is shown in said figures and all the others in the machine are like it.

In portions 7 and 8 of the frame rectangular openings 39 are made to receive the bearing-blocks 40, in which bearing-blocks the shafts of the feed-rollers and the shafts of the cutters have bearings, as indicated by dotted lines in Fig. 2 and shown in full lines in Figs. 95 5 and 6. These bearing-blocks are vertically adjustable in the openings 39, and the adjustability is controlled by the set-screws 41, by which means the feed-rollers and the cutters and their gears may be adjusted as 100 needed.

The adjustable arms 38 are mounted on the bearing-blocks, as in Fig. 6, between the frame portion 8 and the gears on the shafts of the

cutters and feed-rollers. These gears are dotted in in Fig. 5. The adjustable arms 38 are provided with an elongated slot 42, and the idle gears are attached to said arms by a bolt 43 in said slot, so that said idle gears can be adjusted lengthwise in said arms. The portion of the frame 8 is provided with elongated slots 44 at right angles to the adjustable arms 38, and a bolt 45 adjustably attaches the end of the arms to the frame by said bolt passing through the slot in the arm and the slot in the frame portion 8, Figs. 5 and 6. By means of the described provisions the cutter-shafts 10 and 11, the feed-roller shafts 27 and 28, and the idler-gears 33, 34, 35, and 36 can all be adjusted to meet the proper requirements. For instance, when the machine is put together the gears 33 and 34 would be adjusted so as to mesh properly with each other and with the gears 31 and 32. Gears 33 and 36 would also be adjusted to properly mesh with gears 29 and 30. It will be readily seen that while this adjustment is convenient it might not always be necessary. The frame portion 7 in the actual construction would of course be provided with adjustable bearings for the ends of the shafts 10, 11, 27, and 28, like those at 40, above described.

At the rear of and in front of the feed-rollers 16 and 17 is a hollow guide 46, Figs. 1 and 3, said guide being separated where the saws come, as at 47. This guide has an inclined portion 48 at the delivery end, which is shown in longitudinal section in Fig. 3, and down which incline the strip of material is conveyed after being fringed, Fig. 1. This inclined portion of the guide is open at the top, like an uncovered spout. The guide has a rearwardly-extending backboard 148, against which the edge of the material 15 is placed to fix the width of the strip of material being cut. This backboard has an elbow-guard 49, beneath which the material 15 is caught when starting the machine, Figs. 1 and 3. This guard keeps the material straight and smooth, and, what is more important, it prevents the operator from getting his fingers caught between the knives, as he keeps his hands back of this guard. The guide 46 is attached on a plate or shelf 50, the latter of which is attached to the frame portion 7.

Upon operating the machine power would be applied to the pulley of one of the saw-shafts—for instance, pulley 51 on shaft 20; but the pulley might of course be on the other saw-shaft. Power would at the same time be applied to one of the cutter-shafts 10 or 11 by means of a pulley attached to one of said shafts. The gears 52 and 53 transmit power from one saw-shaft to the other, Fig. 1. In Fig. 1 the pulley 100 on the cutter-shaft 10 shows a convenient means for applying power to the cutters.

In the operation the material 15 is placed on the shelf 50, Figs. 1 and 3, and under the guard 49 and passed on between the knives and into the guide 46 and between the feed-

rollers, at which time the saws act upon each edge of the strip of material, making it fringed on each edge, as at 54, Figs. 1 and 4.

Having thus described my invention, what I claim as new, and desire to secure by Letters Patent of the United States, is—

1. A combined carpet cutting and raveling machine for preparing rug material, comprising, revoluble cutters for severing a strip of carpet, said cutters having gear-connected shafts, and one of them provided with means for applying power to the cutters; feed-rollers beyond the cutters, between which rollers the severed strip of carpet passes, gear-connected shafts to said feed-rollers and gear connections between said roller-shafts and the shafts of the cutters; raveling-saws one on each side of the feed-rollers, and having gear-connected shafts and one of them provided with means for applying power to the raveling-saws; and a guide at the contiguous edges of the feed-rollers, and having an opening each side of said rollers for receiving the raveling edges of the saws, substantially as set forth.

2. In a machine for preparing rug material from carpet, revoluble cutters for severing the strip, said cutters having gear-connected shafts; revoluble feed-rollers between which the severed strip passes, said feed-rollers having gear-connected shafts and gear connection between said feed-roller shafts and the cutter shafts, and means for applying power to them; a raveling-saw each side of the feed-rollers and adapted to ravel the edges of the strip, and having gear-connected shafts and means for applying power thereto, all combined, whereby the machine is adapted to cut the strip and ravel the edges thereof in unison in the same machine, substantially as set forth.

3. A combined carpet cutting and raveling machine, comprising, revoluble cutters for severing a strip of carpet, and having gear-connected shafts; feed-rollers between which the severed strip passes, and having gear-connected shafts; gear connections between the cutter-shafts and the feed-roller shafts and means for applying power to them; raveling-saws adapted to ravel the edges of the severed strip and having gear-connected shafts, and means for applying power to them; a guide for directing the severed strip of carpet, and a guard back of the cutters to hold the carpet in place and adapted as well to protect the fingers of the operator, substantially as set forth.

4. The combination with the frame, provided with adjustable bearings, of the rotary cutter and feed-rolls, shafts therefor journaled in said bearings, a feed-table provided with a suitable guide attached thereto adapted to gage the width of the strips into which the material is designed to be cut; the rotary raveling-saws, shafts therefor journaled in bearings in said frame, means for regulating the adjustment of said shafts carrying the said

raveling-saws, according to the depth of raveling desired to be performed, a delivery-table, and suitable means for connecting and operating the feed, cutting and raveling mechanism in conjunction with each other, substantially as set forth.

In testimony of the foregoing I have here-

unto set my hand in the presence of two witnesses.

MARK YOUNG.
